UNITED STATES PATENT OFFICE.

JACOB GENG, OF BRINKMAN, MONTANA.

HAIR-FASTENER.

1,306,589.

Specification of Letters Patent. Patented June 10, 1919.

Application filed June 15, 1918. Serial No. 240,143.

To all whom it may concern:

Be it known that I, JACOB GENG, a citizen of the United States, residing at Brinkman, in the county of Hill, State of Montana, have invented a new and useful Hair-Fastener; and I do hereby declare the following to be a full, clear, and exact description of the invention, such as will enable others skilled in the art to which it appertains to make and use the same.

The present invention relates to a hair fastening device, and has for its object to provide a hair supporting bar which embodies novel features of construction whereby the hair at the back of the head can be quickly dressed in an attractive manner without necessitating the use of more than one or two hairpins, thereby saving much time and annoyance as well as the expense incident to the use of large numbers of hairpins and similar devices.

Further objects of the invention are to provide a hair fastening device of this character which is simple and inexpensive in its construction, which can be readily applied to the hair or removed therefrom, which is not liable to become accidentally disengaged from the hair when in operative position, and which provides an attractive way for dressing the hair at the back of the head.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:

Figure 1 is a side view of a human head in which a hair fastener constructed in accordance with the present invention is utilized for dressing the hair at the back of the head, the hair fastener being shown in the position initially assumed when winding the hair into a coil and before the fastener is rotated into engagement with the back of the head.

Fig. 2 is a view of the back of the head after the fastener has been rotated into its final position, showing the hair fastener and the manner of dressing the hair in connection therewith.

Fig. 3 is an enlarged front elevation of the hair fastener.

Fig. 4 is a top plan view thereof.

Fig. 5 is a transverse sectional view through the middle of the device.

Corresponding and like parts are referred to in the following description and indicated in all the views of the drawings by the same reference characters.

The hair fastener or supporting member is in the form of an elongated bar 1 which may be conveniently formed of sheet material, said bar being of a sufficient length to extend across the back of the head, and being curved longitudinally so that it will conform to the shape of the head and engage the same when it is in operative position. One end of the bar is pointed at 2 and provided at points immediately adjacent thereto with side notches providing laterally projecting arms 3 which may engage and interlock with the hair when the fastener is in operative position. The opposite end of the fastener is notched at 4, the sides of the notches being pointed and extended laterally so as to provide prongs 5 which may interlock and engage with the hair when the bar is in its final position. The middle portion of the bar is provided with side flanges 6 which are returned to provide rounded edges adapted to rotate freely through a coil or twist of hair without catching in the hair and pulling or tearing the same. At intervals throughout the length of the bar projections 7 may be pressed outwardly therefrom, alternate projections being arranged upon opposite sides of the bar. These projections preferably have rounded noses and sharp edges which would cut or tear the hair are avoided.

In utilizing the fastener for dressing the hair, the bar is initially applied to the back of the head in a substantially horizontal position, but with the convex instead of the concave side thereof facing toward the head. In other words, the initial position of the bar is exactly the reverse of the final position thereof, the ends of the bar curving rearwardly in opposite directions away from the head, as indicated by Fig. 1. The hair is wrapped or twisted one or more times around the middle of the bar, as indicated at A, and then wound in a coil between the bar and the back of the head, as indicated at B. This can be readily accomplished,

since the ends of the bar are curved rearwardly away from the back of the head and serve to direct the hair into proper position as it is being coiled. The ends of the hair 5 may either be finally fastened by one or two hairpins, or drawn tightly into position without the use of hairpins. After the hair has thus been coiled, as indicated by Fig. 1, the bar 1 is rotated about a longitudinal axis 10 and the curved ends thereof brought into position at opposite sides of the head, as indicated by Fig. 2. The rounded edges provided by the flanges 6 enable the hair fastener to be rotated in this manner without 15 cutting or pulling the hair, and after the bar has been rotated into final position the arms 3 and prongs 5 at opposite ends thereof can be worked into the strands of the hair so as to hold the bar in proper position. The 20 projections 7 also assist in engaging the hair to support it in the necessary manner. An attractive manner of dressing the hair is thus provided, and the annoyance and expense which is incident to the use of a large 25 number of hairpins is avoided.

Having thus described the invention, what I claim as new and desire to secure by Letters Patent, is:—

1. A hair fastener including an elongated 30 bar adapted to extend transversely across the back of the head and curved longitudinally to conform to the shape of the head, the middle portion of the bar being formed

with longitudinally extending parallel and rounded edges about which the hair can be 35 wrapped with the bar initially positioned so that the ends thereof are curved away from the head, the rounded edges enabling the bar to be subsequently rotated about a longitudinal axis to bring the ends thereof into position at opposite sides of the head, and hair engaging means at the ends of the bar which are brought into operative position when the bar is rotated as above indicated.

2. A hair fastener including an elongated 45 bar adapted to extend transversely across the back of the head and curved longitudinally to conform to the shape of the head, the middle portion of the bar being provided with side flanges which are returned to form 50 rounded edges so that the bar can be rotated about a longitudinal axis to bring the ends thereof into position at opposite sides of the head after the hair has been wrapped around the middle portion thereof, the said ends of 55 the bar being provided with hair engaging prongs, while lateral projections are provided at intervals throughout the length of the bar.

In testimony whereof I have signed my 60 name to this specification in the presence of two subscribing witnesses.

JACOB GENG.
